FLAT WIRE FOR WEAVING SINGLE
PIECE PILE FABRICJohn Krehbiel, Bronx, N. Y., assignor to J. J.
Krehbiel, New York, N. Y.

Application April 8, 1932, Serial No. 603,981

1 Claim. (Cl. 139—37)

This invention relates to the use of flat wires disposed in the direction of the warp in the manufacture of pile goods. More particularly such wires are here used for gaging the distance to which the pile extends from the ground web and for supporting the pile loops.

Wires have been previously employed in the manufacture of pile fabric, which were inserted in the direction of the weft, either simultaneously with the weft, as 10 with the weft or alternately with the weft, as the weave construction may require. Looms used for this purpose have a special mechanism for inserting such wires in the direction of the weft and are therefore called wire looms. The pile 15 was formed by looping warp threads around the wires in a sequence as required by the weave construction.

The insertion of such wires in the direction of the weft through the shed can only take place 20 gradually and slowly, which fact considerably reduces production on the said wire looms.

This invention relates to a new method of employing wires for the purpose of creating fabrics similar to those produced by wire looms. Contrary to the arrangement of the wires in the wire 25 loom, which are inserted in the direction of the weft, this invention provides for wires which are arranged stationarily in the woven fabric in the direction of the warp, and which extend from the 30 fell of the fabric over several repeats toward the take-up. They are exchangeable, (allowing variations in height and length) according to the tension applied to the threads which are engaged upon said wires, and according to the characteristics 35 of said threads, i. e., in accordance with the quality and density of the fabric, said wires are suitably made longer or shorter.

These stationary wires carry a pile support weft 40 inserted above them, the weft being supported firm enough to support in turn the pile forming threads. In other words, the pile weft resting on the stationary wires serves the same purpose as the weft-wise inserted wire of the wire loom. By changing the height of these stationary wires, 45 the height of the pile can be controlled much more readily than by the wires of the wire loom; because the wire of a wire loom is limited to the size of the shed into which it is inserted, while the stationary wires or gages used in this invention are not limited in that respect.

The stationary wires of my invention must be constructed so that a part thereof can be raised and lowered around a joint laying in the fell of the fabric, in order to permit the formation of a 50 shed for the purpose of inserting various wefts.

For this purpose a stationary section of the wires mentioned above is hingedly or flexibly connected with another wire which may be raised or lowered as the shed may require. This swinging wire section or link serves at the same time for keeping 5 the stationary wires in place so that they move neither to the front nor back of the fell of the fabric.

In raising and lowering the other wire section or link for the purpose of forming the shed, the 10 end thereof must be swung in a circle around the point at which it is joined, hinged, linked or otherwise connected with the stationary part of the wire.

This invention has therefore the object of providing 15 for a circular motion of the end of the movable wire or link while it retains the gage in a stationary position, and means are provided for supporting and actuating the link accordingly.

It is also clear that the more the shed wire, 20 link or movable wire is moved up or down from a horizontal position, the larger will be the longitudinal clearance space required for its swinging, free end. Inasmuch as that space must be provided for additionally to the harness space, it 25 should be limited to a minimum. This invention therefore provides for a shedding motion which places the center of the shed in a horizontal line with the stationary wire section, so that the shed wire, when a shed is formed, travels 30 like distances up or down from said center which are larger or smaller as the type of the fabric and the size of the shuttle may require.

My invention will be better understood from the following description referring to the accompanying 35 exemplary and partly schematic drawing, in which:

Fig. 1 shows, in a longitudinal section, part of a loom to which my invention is applied.

Fig. 2 shows the corresponding loom parts in 40 a parallel perspective view, illustrating a modification of my invention.

Fig. 3 illustrates, in a parallel perspective detail view, the exchangeability of the stationary wire or gage.

Fig. 4 shows a similar detail view of the heddle which retains said gage.

Fig. 5 illustrates, by a longitudinal cross-section, another modification of this invention.

Similar numerals refer to similar parts 50 throughout the various views:

The finished pile goods 11 travel to the left over a support 12 in Fig. 1. The pile loops 14 are supported by the wefts 13 of the upper filling, whereas the body of the weave 15 is spaced therebelow. 55

Upon the lower filling or ground web 15 rest the stationary wires 16, which hereinafter will be referred to as the gages. The gages support the wefts 13 of the upper filling which slide off the gages when the goods 11 travel to the left. The gages 16 are rotatably swingable around the end of movable wires 17 which hereinafter will be referred to as the links. These links also circumscribe the shed during their movements, in which 10 travels the shuttle 18 in front of a reed 19. The links 17 extend through the reed 19 and are engaged upon vertical wires 20 which will hereinafter be referred to as heddles. The heddles are mounted in the customary manner in a vertical 15 ly (arrow 21) reciprocating heddle frame.

The links 17 are attached to the heddles 20 in the following manner. The heddle 20 consists of two blades 22 and 23 (Fig. 4) which are spacedly connected by a rivet 24. The space allowed between the blades 22 and 23 by means of the rivet 24 allows free movement of the link 25, the rivet 24 extending through a longitudinal slot 26 at the end of the wire 25.

If we consider the gage 16 stationary, the end of the link 17 will swing along a circle 27 during the reciprocations of the heddle 21. The shed is arranged substantially centrally between the extreme positions of the link 17 in its up and down movements. The lowest position of the link is indicated by the numeral 17, its center position by 17a and its highest position by 17b. The slot 26 is of such length, that it allows free movement along said slot during the reciprocation of the heddle 21. In the extreme up and down positions 17 and 17b of the link, the rivet slides into the extreme corner of said slot 26. The gage 16 is however not stationarily supported, but rests upon the slowly moving goods. Therefore it will slowly travel to the left, unless the extreme corner of the slot 26 in link 17 is engaged by rivet 24 whenever the link reaches its highest and lowest position, so that the gage 16 is slightly pulled to the right to whatever extent it has moved to the left by travelling with the moving goods 11. Thus the gage is pulled out of the goods, which slide from the gage at the left. The warps 41, 42 and 43 form the shed together with the links, completing the exemplary showing of a fabric.

Fig. 2 shows gages 16 and heddles 20, similar to those of Fig. 1, and shows the heddles to be mounted in a heddle frame 28, which is suspended between cords 29, engaged on hooks 30 on the frame. The said cords are pulled up and down in the manner well known to those acquainted 55 with the art of textiles. The link 31 of Fig. 2 differs from the link 17 of Fig. 1 by not having any slot 26. It is rotatably hinged at its free end upon the rivet 24 connecting the blades to the heddle 20. In an arrangement of this kind, the gage 16 would of course be pulled back and forth in a horizontal direction while the heddle frame moves up and down. Such movements of the gage 16 would interfere with the weaving and the proper forming of a shed; they are avoided

by oscillating the heddle frame, i. e. by moving the heddle frame along a curve so that the gage 16 remains stationary and the link 31 swings around the point at which it is hinged upon said gage.

The movement of the heddle along a curved path is brought about in the following manner:— Two brackets 32 and 33 extend from the stationary frame of the loom. Two brackets 34 and 35 are mounted upon the cross members of the 10 heddle frame 28. The stationary brackets 32 and 33 and the brackets 34 and 35 are connected to each other, respectively, by connecting rods 36 and 37, the length between the centers of which corresponds to the distance between the points at 15 which the link 31 is hinged upon the gage 16, and the heddle 20. The connecting rods 36 and 37 are disposed substantially parallel to the links 31. The heddle frame 28 will therefore swing through a curve, while being pulled up and down by cords 20 29, so that the rivet 24 swings in a circle around the end of gage 16, at which the link 31 is fastened thereupon.

The heddle frame may also be caused to move in such a manner that the link 31 swings around 25 the end of gage 16, by an arrangement like that shown in Fig. 5. Here a pin 38 extends from the end of the frame 28 and is guided by a groove 39, in a bracket 40 mounted on the loom (not shown). There is also the difference between this arrangement and that of Fig. 2, that the upper end of the frame moves along a vertical path, the groove 39 being curved more than the path along which swings the rivet 24 around the end of gage 16, so that the rivet 24 follows the desired path around 35 the end of the stationary gage 16.

The principle of Fig. 2 in which both the ends of the heddle frame are guided may of course also be applied to the pin and groove arrangement of Fig. 5, and vice versa.

While I have shown and described my invention with some degree of particularity, it will be realized that other modifications and changes may be resorted to under special conditions. I therefore do not wish to be limited and restricted to 45 the exact details shown and described, but reserve the right to make such changes and modifications as may fairly fall within the scope of the subject matter being claimed.

What I claim is:—

In combination with a loom weaving a fabric with superimposed pile-supporting wefts, longitudinally disposed gages spacing said fabric and said wefts apart, a frame, shed-forming links connecting said gages to said frame, a mechanism raising and lowering said frame, and a lever parallel to said links, swingably supporting said frame on said loom and guiding said frame when raised and lowered; so that said links are swung in an 55 arc around the point and fulcrum at which the links are connected to said gages and which is thus rendered stationary relatively to the loom.

JOHN KREHBIEL.
